Primary Examiner — Susan Moon Lee(74) *Attorney, Agent, or Firm* — Williams Intellectual Property; Benjamin F. Williams(57) **CLAIM**

The ornamental design for a handheld pet washing device, as shown and described.

DESCRIPTION

FIG. 1 is an isometric view of a handheld pet washing device in accordance with the present design;

FIG. 2 is an isometric view of the handheld pet washing device with the straps fastened;

FIG. 3 is a top plan view thereof;

FIG. 4 is a bottom view thereof;

FIG. 5 is a right side elevation view thereof;

FIG. 6 is a left side elevation view thereof;

FIG. 7 is a rear elevation view thereof; and,

FIG. 8 is a front elevation view thereof.

1 Claim, 8 Drawing Sheets(56)
